SPLASH GUARD FOR MACHINE TOOLS AND LIKE PURPOSES

Dan S. Hermansson, Munkedal, Sweden

Application September 6, 1957, Serial No. 682,421

5 Claims. (Cl. 51—272)

The present invention generally relates to splash guard devices, and more particularly to splash guards adapted for use on machine tools or the like, such as grinders, lathes, etc., having means for supplying a cooling and/or lubricating fluid to the tool proper or to the work being machined, and in which the splash guard comprises a transparent panel which is movable from an active to an inactive position in order to enable work pieces to be positioned and removed, respectively.

A primary object of the present invention is to provide a splash guard of the kind referred to which is bodily displaceable from its operative position.

Another object of the invention is to provide a splash guard of the kind stated having its movable panel so disposed and arranged as to enable the machine operation to be observed continuously without the necessity of removing the splash guard from its operative position.

Another object of the invention is to provide a splash guard of the kind stated in which the splash guard is adjustable into various positions to adapt the same in accordance with various requirements.

A further object of the invention is to provide a splash guard device of the kind referred to which is extremely simple to handle in operation.

For the objects thus stated, in accordance with the present invention, a splash guard device of the kind referred to is further characterized by comprising first guiding means for two oppositely disposed edges of said transparent panel, this panel being substantially rectangular in shape, said guiding means extending at right angles to the longitudinal axis of said machine tool whereby said panel is displaceable along a path extending substantially transversely relative to said axis, and said guiding means being further carried by two opposite side members of a frame structure which is so arranged as to be displaceable in a direction parallel to the longitudinal axis of said machine tool and to be locatable in various positions of displacement, said frame structure being thus displaceable along second guiding means extending in spaced parallel relation to the longitudinal axis of said machine tool, one of said second guiding means providing pivot means about which said frame structure is swingably mounted to enable said frame structure together with said movable panel to be swung out of its operative position.

In a preferred form of the splash guard device as stated in the preceding paragraph, said second guiding means are in the form of rods which are circular in cross-section.

Further features and advantages of the present invention will become apparent from the following description thereof in conjunction with the accompanying drawing which illustrates a preferred embodiment of the invention, and in which:

Fig. 1 is a front elevation of the novel splash guard device, and

Fig. 2 is a left-hand end elevation of the splash guard

2

shown in Fig. 1, but with the transparent panel thereof moved into its inactive position.

Referring now to the drawing more specifically, numeral 1 designates a portion of a machine tool which is diagrammatically indicated in part only, the remainder of the machine tool—which is assumed in the present case to be a grinding machine—being completely omitted for simplicity of illustration since the machine proper forms no part of the present invention. Numerals 2 and 3 designate two panels of which one, viz. the panel 2, is a sheet-metal plate which extends at an angle upward and outward from the front edge portion of the table 1, whereas the other panel 3 is transparent and may conveniently be made of shatterless glass or any suitable other material. The first-mentioned panel 2 at its lower edge engages a longitudinal groove 4 formed in said edge portion of the table 1, and at its upper edge said panel 2 is connected with the remainder of the splash guard. The last-mentioned connection may be either detachable or rigid.

The transparent panel 3 is surrounded by a closed metal frame 5 and is substantially rectangular in shape, two oppositely disposed edges of the panel 3 co-operating with corresponding guides 6 extending substantially at right angles to the longitudinal direction of the table 1, the non-illustrated longitudinal axis of the machine tool being parallel to the last mentioned direction. The guides 6 which may be channel-shaped in cross-section and with which the panel 3 co-operates through the intermediary 25 of the closed frame 5, form two oppositely disposed side members of a substantially rectangular frame structure 7 which is displaceable in the longitudinal direction of the table 1 by being slidable along rods 8, 9 serving as guiding members for this displacement. These rods 8, 9, 30 extending in spaced parallel relation to the longitudinal direction of the table 1, are carried by upright members 10, 11 the foot ends of which are secured to cross-members 12 which are suitably detachably connected with the table 1 and extend transversely across the top of this 35 table.

In its active position as shown in Fig. 1, the panel 3 is retained against displacement from this position by a spring-loaded latch 13 engaging a shoulder 14 provided on the lower member of the closed frame 5 of the transparent panel 3. The latch 13 is fulcrumed at the lower member of the frame structure 7 and is formed by a double-armed lever of which one arm forms the latch proper while the other arm is acted on by a compression coil spring 15 which urges the latch towards its latching position. The transparent panel 3 is actuated by two springs (not shown) which are disposed within individual tubes 16 to which one end of the respective springs is secured. The opposite end of each such spring is connected to a wire 17 which runs about a pulley 18 and is secured to the frame 5 of the transparent panel 3. The last-mentioned two springs are tension coil springs which urge the panel 3 upward towards the upper member of the frame structure 7, i. e. away from its active position shown in Fig. 1. The wire pulleys 18 are journaled on the rod 8 which is formed as an axle of circular cross-section and serves as a guiding member for the sliding frame structure 7.

The frame structure 7 is provided at its upper longitudinally extending member with lugs 19 apertured for the rod or axle 8, whereby the frame structure 7, together with the transparent panel 3 and possibly the panel 2 also, is swingable about the axle 8 so as to enable the splash guard to be moved bodily away from its operative position. To enable this, the rod 9 may be retractable, or alternatively it may be so devised as to accompany the splash guard in its angular movement about the axle 8. The mode of operation of the splash guard described

hereinbefore would be obvious from the description thus furnished and from the accompanying drawing, and it need only be mentioned here that, owing to the presence of the transparent panel 3, it will be possible to observe and check the progress of the machining being carried out, without the necessity of moving the splash guard away from its operating position. Further, it will be possible to adjust the splash guard into various positions in order to adapt the same to various practical requirements. In addition, the operation and handling of the splash guard is seen to be extremely simple.

It will be obvious to anyone skilled in the art the structural realization of the present invention is by no means restricted to the sole embodiment described hereinbefore and as illustrated in the accompanying drawing, but that the same is susceptible of variations and modifications in its details without departing from its scope.

What I claim is:

1. A splash guard device for use on a machine tool of the type having fluid supplied to the tool and workpiece, comprising in combination a pair of guide rods secured to the machine parallel to its longitudinal axis and fixed in spaced planes, a rectangular frame, means to slidably attach said frame to said guide rods, the upper attaching means providing for pivoting of the frame about its corresponding rod as an axis, a transparent panel carried by said frame, and guide means for the lateral edges of the panel formed on said frame whereby said panel may be moved in a direction normal to the machine axis to permit access to the tool and workpiece.

2. A splash guard device for use on a machine tool of the type having fluid supplied to the tool and workpiece, comprising in combination a pair of guide rods secured to the machine parallel to its longitudinal axis and dis-

posed in spaced planes, a substantially rectangular frame structure pivotally and slidably supported by said guide rods for motion parallel to the machine axis and for rotation about the upper rod as a center, a transparent panel carried by said frame structure movable from an active to an inactive position to permit access to the workpiece and tool, and guide means for two parallel edges of said panel formed on said frame extending normal to the axis of the machine whereby the panel is movable along a path extending transversely relative to the axis.

5 3. A splash guard according to claim 2 comprising energy storage means urging said transparent panel away from its active position, and latching means for retaining said panel in its active position against the action of said energy storage means.

15 4. A splash guard according to claim 2 comprising resilient means urging said transparent panel away from its active position, and latching means for retaining said panel in its active position against the resiliency of said 20 resilient means.

25 5. A splash guard according to claim 2 comprising springs urging said transparent panel away from its active position, and self-engaging latching means for retaining said panel in its active position against the resiliency of said 25 of said springs.
